UNITED STATES PATENT OFFICE.

ROBERT W. A. BREWER, OF PHILADELPHIA, PENNSYLVANIA, ASSIGNOR TO HAROLD F. PITCAIRN, OF BRYN ATHYN, PENNSYLVANIA.

VALVE MECHANISM FOR INTERNAL-COMBUSTION ENGINES.

Application filed March 9, 1925. Serial No. 13,992.

The main objects of this invention are:—

1. To provide a light and flexible sleeve valve of novel construction for an internal combustion engine, which can be made easily and cheaply in the form of a metal pressing.
2. To construct this novel valve so that it can be mounted in the engine easily and cheaply.
3. To provide a water-cooled cylinder head with an ample supply of water from the cylinder jackets and to utilize the water-carrying element as a locating and fixing means for the cylinder head closing member, and lastly
15. 4. To arrange the ports so that the cylinder head, the water-carrying element and the cylinder head closure element shall be firmly tied together in a simple manner and the casting forming the bridges between the port openings will be relieved to a great extent from the stresses caused by the burning of gases inside the cylinder.

According to this invention, in an internal combustion engine the valve member consists of a cup-shaped pressing, the outer circumference of which makes contact with the cylindrical portion of the bore of the combustion chamber. This cylindrical portion is preferably provided with saw cuts or corrugations not herein shown but described in a contemporaneously pending patent application filed by me, and it may be further provided with circumferential slots or openings to suit the requirements of the port arrangement of the engine to which my novel valve mechanism is adapted, my present invention consisting in the practical application of this novel valvular construction so that it can be put into commercial usage in quantity production. A further feature of my present invention consists in the use of a hollow, metal bridge piece attached to the cylinder head closure member by a screw threaded plug extension or by a number of separate screws or the like. After my novel valve member has been placed in position over the closure plug, the bridge piece is then inserted through the transverse opening in the valve member and screwed to the closure plug and the complete unit mounted on the cylinder head and held firmly thereto by studs or screws, which pass through the cylinder head and screw firmly into the lower face thereof, thus transmitting the working stresses directly to the cylinder head face

and relieving the cast iron of the port construction from tension. The actuation of the valve can be carried out by any known means, such as the usual cam actuated tap-pet and lever, acting in both directions or in one direction with a spring return, which is unnecessary to describe in detail. The valve can also be actuated by direct cam contact as described in Patent No. 1,439,894.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Referring to the accompanying drawings, Fig. 1 is an elevation of my novel valve, a portion being taken away. Fig. 2 is a section on line 2—2 of Fig. 8. Fig. 3 is a top plan of the valve in position on the cylinder head. Fig. 4 is a half elevation of the bridge piece. Fig. 5 is a bottom plan view of Fig. 4. Fig. 6 is a section of Fig. 4 on line 6—6. Fig. 7 is a perspective view of my novel valve in detached position. Fig. 8 is a vertical section on line 8—8 of Fig. 2 with the valve removed. Fig. 9 is a part section on line 9—9 of Fig. 3 through the center of the valve in position with the water-carrying bridge piece in elevation. In these drawings similar numbers apply to similar parts.

1 designates my novel valve, which may be formed as a pressing or other convenient construction having the closed top upon which is an extension or eye 2, forming one means of attachment to any suitable operating means. 3 is the skirt of the valve to which is imparted a degree of flexibility by reason of the longitudinal saw cuts or openings 6, which extend from the bottom of the valve upwardly. 4 designates transverse ports cut through the wall of the valve 1, adjacent to the saw cuts 6. 5 is the lower edge of the valve which serves to open the inlet port 9, when the valve is reciprocated upwards. The exhaust port 8, is uncovered by the port 4, in the valve, when the valve is reciprocated downwards. These ports lead respec-

tively to the passages 11 and 10 and in the design shown, the lower ring of ports 9, has an outlet on each side of the engine and is adapted to carry the inlet gases in preference to the exhaust gases, because the joint between the cylinder head and the cylinder proper can thereby be kept cooler and relieved of practical difficulties which frequently occur in keeping such a joint tight 10 under extremes of temperature which may occur, were the functions of the two passages, 10 and 11, reversed. In my present invention, the common wall between the inlet and exhaust passages serves to assist in the 15 vaporizing of the fuel and the flat floor of the inlet passage further assists the flow of fuel to the engine in a desirable manner. The bridge piece 12, is preferably constructed as a hollow, rectangular box suitably secured to the main casting of the cylinder head and provided with an externally threaded plug or extension 17, adapted for firm attachment to the cylinder head closure member 14, and acting as a water conduit 20 through passage 16, between water chamber 21, of said member 14, and the water jacket 22, of the cylinder head 20. As an alternative construction, these two members, 12 and 14, may be faced, flanged, and attached to 25 one another by screws. The portion of the closure plug 14, which is shown at 19, serves to retain the pressure sealing ring 15, in position. It further provides an abutment upon the member 12, close to the holding 30 down studs 13, which pass through the openings 18, so that direct thrust upon the head 14, is transmitted to the studs 13, without causing undue bending stresses in the member 12.

35 40 Lubrication of the mechanism is provided by permitting the valve in its downward movement to overrun a portion of the cylinder bore and pick up excess oil which has passed along the cylinder walls above the piston travel.

45 It will be apparent from the foregoing that my novel valve and its adjuncts, can be cheaply constructed, and readily mounted with respect to the engine, and that the 50 cooling elements can also be readily assembled and will function effectively for the purposes intended.

55 Having thus described my invention, what I claim as new and desire to secure by Letters Patent, is:—

1. In an internal combustion engine, a cylinder head having circumferential ports therein, a flexible metallic sleeve valve slidably mounted within said cylinder head to

control said ports, a cylinder head closure 60 plug within said valve, a hollow bridge piece passing transversely through said valve and attached to said plug thereby permitting limited axial movement of said valve with respect to said plug and bridge piece, 65 means for attaching said bridge piece to said cylinder head and means for reciprocating said valve.

2. In an internal combustion engine, a cylinder head having circumferential ports 70 therein, a comparatively flexible curvilinear valve positioned in said head and juxtaposed to said ports, a hollow cylinder head closure plug within said valve, means for conducting water to said hollow plug, comprising a 75 supporting bridge piece for contacting with the outer rim of said closure plug and means for reciprocating said valve.

3. In an internal combustion engine, a cylinder head having circumferential ports 80 therein, a water jacket therefor, a curvilinear valve controlling said ports, said valve comprising a flexible, dome-shaped cylinder, 85 openings disposed around said cylinder head, a water cooled bridge piece passing through said openings, a water cooled cylinder head closure plug within said valve attached to said water cooled bridge piece, means for securing said bridge piece to the cylinder head water jacket and means for 90 reciprocating said valve.

4. In an internal combustion engine, a cylinder head having circumferential ports therein, a water jacket therefor, a flexible 95 curvilinear valve controlling said ports, a hollow cylinder head closure plug within said valve, a flexible sealing ring associated with said plug and valve, a hollow bridge piece attached to said plug and holding said ring in position in the upper end of said 100 plug, means for securing said bridge piece to the cylinder head water jacket and means for reciprocating said valve.

5. In an internal combustion engine, a cylinder head having a circumferential port 105 therein, a water jacket therefor, a curvilinear valve controlling said port, a hollow bridge piece, a hollow cylinder head closure member juxtaposed to said hollow bridge 110 piece and attached thereto, means for securing said bridge piece to the water jacket of the cylinder head, said means comprising screw members passing through said bridge piece and through passages in the cylinder head and secured to bosses formed on the solid metal of the walls of the structure and means for reciprocating said valve.

ROBERT W. A. BREWER.
